UNITED STATES PATENT OFFICE.

PAUL FELIX AUGUSTE RACINE, OF MARSEILLE, FRANCE.

APPARATUS FOR STORING AND DISTRIBUTING DANGEROUS LIQUIDS.

Application filed March 26, 1919. Serial No. 285,396.

To all whom it may concern:

Be it known that I, PAUL FELIX AUGUSTE RACINE, citizen of the Republic of France, and resident of Marseille, 32 Rue Breteuil, 5 France, have invented a new and useful Apparatus for Storing and Distributing Dangerous Liquids; which improvements are fully set forth in the following specification.

10 This invention relates to a device for storing dangerous liquids, by means of which evaporation of the liquid, and its escape through the wall of the tank, can be avoided.

Evaporation of dangerous liquids is 15 avoided by always keeping the tank full owing to an auxiliary liquid which makes up for the dangerous liquid discharged and can, if it be advisable, be used to displace the dangerous liquid without the latter having 20 to pass through pumps.

Escape of the dangerous liquid through the wall of the tank is avoided by surrounding the tank with a safety liquid, the pressure of which is higher than that of the 25 dangerous liquid. In case of a crack or porosity of the wall, it will be the safety liquid that will get in, and not the dangerous liquid that will get out.

The safety liquid may or may not be the 30 same as the auxiliary liquid.

If the nature of the dangerous liquid, or the impermeability of the tank, make it possible, either the auxiliary liquid or the safety liquid may be done away with.

35 The process could be used not only for dangerous liquids, but also for any liquids.

The accompanying drawing represents a diagrammatic vertical sectional view of one embodiment of the invention; it being assumed that in this instance the dangerous liquid is petrol, the safety liquid water, and the auxiliary liquid also water.

R¹ is the tank containing the safety liquid, i.e. water.

45 R² is the tank containing at the top the dangerous liquid (petrol) and in the bottom part the auxiliary liquid (water).

T is a tube communicating with the bottom of the tank R², in which the auxiliary 50 liquid rises and balances the pressure of the liquids contained in the tank R². It is through the said tube that takes place the movement (admission or discharge) of the auxiliary liquid. It will be observed that 55 this tube or pipe T includes a portion which is disposed vertically in the space be-

tween the two tanks R¹ and R²; and that it is this vertical portion which opens at its lower end into the bottom of the tank R², said portion terminating at its upper 60 end at a point substantially level with the top of the tank R². This arrangement has the effect of protecting the aforesaid vertical portion against injury, accidental or otherwise, since said portion is disposed 65 within the confines of the outer tank R¹; and it also renders the apparatus somewhat more compact for the same reason.

It is the tube in which takes place the movement (admission or discharge) of the 70 petrol.

In the construction illustrated, the working is as follows:

In order to store petrol, the tank R² being full of auxiliary liquid (water), the 75 cock T² is kept open, and the cock t² closed, and petrol is poured into the funnel t¹; petrol will flow into the tank, and an equivalent quantity of water (auxiliary liquid) will be discharged through the overflow 80 cock T² or by any other means. In order to deliver petrol, the cock t² is opened, the overflow T² is closed, and through the funnel T¹ or any other means water (auxiliary liquid) is introduced into the tank R²; this 85 water will expel the petrol which will escape through the cock t².

If cracks appear in the tank R², it will be water from R¹ that will get into the tank R², at the bottom of which it will collect, 90 and it will be discharged, if necessary through the overflow T² or any other means.

As already stated, the accompanying drawing is merely an example, and the principle will be adapted to suit the individual 95 cases, particularly when the densities of the dangerous liquid, of the safety and of the auxiliary liquids are in proportions other than those in the example described.

What I claim as my invention and desire 100 to secure by Letters Patent is:—

Apparatus for storing and dispensing liquids, comprising an outer receptacle to contain liquid; an inner receptacle disposed within the outer receptacle; and solely two 105 pipes connected to the apparatus, both of which pipes are connected to the inner receptacle and one of which has a portion disposed vertically in the space between the outer and inner receptacles said vertical portion opening at its lower end into the bottom of the latter receptacle and terminating 110

at its upper end at a point substantially level with the top of the inner receptacle to alternatively supply a liquid to the inner receptacle or discharge it therefrom; the other pipe being disposed above the inner receptacle and opening at its outlet end into the top thereof to alternatively supply a non-miscible liquid thereinto upon the top of the liquid supplied by the first-named 10 pipe or discharge the non-miscible liquid therefrom; said inner receptacle being completely submerged in the liquid contained in the outer receptacle but entirely devoid of communication with the same so as to

constantly maintain at all points on the 15 outer surface of the wall of the inner receptacle a pressure which is constantly greater than the pressure exerted by the non-miscible liquid against the inner surface of said wall.

In testimony whereof I have signed this specification in the presence of two subscribing witnesses.

PAUL FELIX AUGUSTE RACINE.
